UNITED STATES PATENT OFFICE.

JAMES L. BANCROFT, OF CLEVELAND, OHIO.

DRIP MOLDING.

Application filed November 8, 1922. Serial No. 599,644.

To all whom it may concern:

Be it known that I, JAMES L. BANCROFT, a citizen of the United States, residing at Cleveland, in the county of Cuyahoga and State of Ohio, have invented a certain new and useful Improvement in Drip Moldings, of which the following is a full, clear, and exact description, reference being had to the accompanying drawings.

10 This invention relates to what is known as drip molding that is used about the top of closed bodies of automobiles or other conveyances for catching the water that drains from the top and carrying it to the rear so as to prevent the water from flowing down over the windshield and windows.

My object is to provide an inexpensive drip molding that is easy to apply, that requires no hand finishing after applying, and which is neat and attractive in appearance.

In the accompanying drawing, wherein I have illustrated one form of my improved drip molding, Fig. 1 is a fragmentary side elevation of an automobile of the enclosed type having my drip molding applied thereto; Fig. 2 is an outside perspective view of the molding; Fig. 3 an inside perspective view thereof; and Fig. 4 a transverse section through the molding on an enlarged scale.

The drip molding, designated generally by the letter A, comprises a wall strip 1 and a drain trough 2 that are suitably formed from a piece of sheet metal of appropriate thickness, preferably about twenty gauge, sufficiently heavy in any event to render satisfactory service and to retain its shape under normal use, though not too stiff, however, to readily adapt itself to the contour of the wall when applied thereto. According to my present design, the wall strip 1 is curved outwardly between its upper and lower edges to form a shallow channel, and its lower edge connects, through a straight portion 3, with the inner edge of the trough 2. The trough extends downwardly and outwardly and then upwardly to about the horizontal plane of the lower edge of the wall strip.

At suitable intervals along the drip molding, attaching means 5, such as nails, are secured to the wall strip by having their overturned inner ends or heads 6 embedded

within deposits of suitable material, such as 55 lead, indicated at 7 in Figs. 3 and 4, that occupy the channel of the wall strip.

In applying the molding, it is first properly positioned along the wall of the vehicle and the attaching means or nails 60 are then driven into the wall by hammering the wall strip in the immediate vicinity of the nails, and when the nails are firmly driven into the wall the upper and lower edges of the wall strip are in firm contact 65 with the wall of the vehicle. So applied, the job is ready for the painters so far as the drip molding is concerned.

Heretofore, in connection with all forms of drip molding known to me, it has been 70 necessary to do considerable finishing after the molding is applied; as, in some instances, the nails are driven through a wall flange of the molding after which a lip that extends along the upper edge of said flange 75 is turned down over the nail heads to conceal them; while in others, as for instance, with what is known as the extruded aluminum drip molding, holes are punched through the wall engaging flange of the 80 molding, leaving a part of the metal which is punched from the holes attached to the molding and after the nails or brads are driven through said holes for securing the molding to the wall, the said metal is 85 peened over into the holes to fill them and conceal the nail or brad heads. In this and in the previous case it is necessary for the workman to spend considerable time in smoothing and filing the molding in order 90 that it may present a finished appearance. Also, there are drip moldings which may be attached by nails or screws which have no provision for covering the screw or nail heads, but these are objectionable because of 95 their unfinished appearance.

My invention provides a simple and inexpensive drip molding that may be conveniently and quickly applied, is equipped with attaching means so that the workman 100 does not have to contend with loose nails or the like, which adheres closely to the surface of the wall throughout its length, requires no finishing other than painting, and presents an attractive appearance.

In the furtherance of quality and economy I propose to make my drip molding of sheet metal properly rust-proofed.

Having thus described my invention, what I claim is:

1. A drip molding comprising a wall strip of channel form and a trough extending along the lower edge of the wall strip, attaching elements suitably spaced apart longitudinally of the wall strip and having heads disposed within the channel of the wall strip, and suitable material within said channel and wherein the said heads of the attaching elements are embedded.
2. A drip molding comprising a wall strip that is curved outwardly between its upper and lower edges thereby to provide a chan-

nel, and a trough formed integral therewith and extending downwardly and outwardly and then upwardly from the lower edge of the wall strip, attaching elements suitably spaced apart longitudinally of the wall strip and having heads reposing within the channel of the wall strip, and suitable material deposited within the channel of the wall strip and wherein the heads of the attaching elements are embedded.

In testimony whereof, I hereunto affix my signature.

JAMES L. BANCROFT.
